CLAIM

The ornamental design for a floppy-disk drive security lock, as shown and described.

DESCRIPTION

FIG. 1 is an enlarged perspective view of a floppy disk drive security lock showing my new design, the disk drive is shown in broken lines for illustrative purposes only and forms no part of the claimed design; FIG. 2 is a top plan view thereof;

FIG. 3 is a right side elevational view thereof, the left side elevational being a mirror image;

FIG. 4 is a front elevational view thereof;

FIG. 5 is a back elevational view thereof; and,

FIG. 6 is a bottom plan view thereof.

FIG. 1

FIG. 2

FIG. 3

FIG. 4

FIG. 5

FIG. 6
